INVENTOR

Reiner W. Erdle

BY *Albert J. Day*

ATTORNEY

UNITED STATES PATENT OFFICE.

REINER W. ERDLE, OF WEEHAWKEN, NEW JERSEY, ASSIGNOR TO THE COLD LIGHT MANUFACTURING COMPANY, A CORPORATION OF COLORADO.

SELF-LUMINOUS DEVICE.

1,363,854.

Specification of Letters Patent. Patented Dec. 28, 1920.

Application filed May 16, 1918. Serial No. 234,846.

To all whom it may concern:

Be it known that I, REINER W. ERDLE, a subject of the Emperor of Germany, who have declared my intention of becoming a 5 citizen of the United States, and now residing in Weehawken, in the county of Hudson and State of New Jersey, have invented certain new and useful Improvements in Self-Luminous Devices, set forth in the following specification and illustrated in the accompanying drawings.

My present invention relates to an improved form of self-luminous pendant intended to be used as an attachment to any 15 article which it is desirable to find promptly in the dark; and more particularly to devices of this character adapted to be attached to the slender chains commonly used for operating the switches on incandescent 20 electric lamps. The object of my invention is to provide a pendant of this character which can be easily and cheaply manufactured and which, when finished, is ornamental in appearance and can be readily and 25 easily fixed to the switch operating chains already commonly in use.

The invention comprises, broadly speaking, a hollow transparent outer container with means for suspending the same, and a 30 transparent inner receptacle containing a self-luminous material and adapted to be inserted readily within the outer container.

I have illustrated certain preferred forms of my invention in the accompanying drawings, wherein Figure 1 is a vertical section of one form of my device, Fig. 2 is a side elevation of the same viewed at right angles to the aspect of Fig. 1 and showing the spun shell in section, Fig. 3 is a vertical sectional 40 view of another form of my device, and Fig. 4 is a sectional view of a modified form of inner receptacle. All of these views show the device much exaggerated in size.

The inner receptacle 13 contains a mass 45 10 of self-luminous material, which is preferably in the form of a fine powder, as used in the form of my device shown in Figs. 1 and 2. This receptacle, as there shown, takes the form of a thin tube of glass which 50 is first sealed by fusion at one end, as at 9, then partly filled with a self-luminous powder, and then sealed at its opposite end 12 by fusion in a well known manner. A space 55 16 should be left at one end, both in order not to interfere with perfect sealing, and in

order that the properties of the self-luminous powder may not be impaired by the heat used in sealing.

The receptacle 13 thus prepared is adapted to be readily inserted into the narrow 60 bore of a thick glass container 14 of suitable shape and size to be used as a pendant upon the chain or other article to be located in the dark. For greater security the opening of the bore is closed by a stopper 15 of 65 asbestos or other suitable material. In Fig. 1, the inner receptacle is shown inclining at an angle which exaggerates the actual inclination probable in practice. This inclination is merely to emphasize the fact that I 70 prefer to make the bore of the outer container sufficiently larger than the diameter of the receptacle 13 to insure easy admission of the latter in all cases.

The container 14 may be made of any 75 suitable transparent or translucent material, and any suitable means may be employed for fastening the same to the chain or other article to be located. I prefer, however, to use the construction shown in my drawings. 80

Here the container 14 is provided with a circumferential groove 17 near its upper end, and a shell 18 of thin metal has its lower edge spun into said groove so as tightly to secure it to the container. This 85 shell may be given any desired ornamental shape. Through an opening in the top of the shell are introduced the ends of a wire loop 19, and these ends are bent outward in opposite directions, as at 20, so as to rest 90 against the inner surface of the shell and prevent rocking of the loop in a direction represented by the plane of the paper in Fig. 1. In order further to stabilize this loop, which serves as the direct suspending 95 agent for the whole device, I prefer to so shape it that the sides of the loop bear normally against the outer surface of the shell and thus prevent rocking in the plane of the paper in Fig. 2.

In the form shown in Fig. 3, the inner receptacle consists of a short length of thin glass tubing, 21, open at both ends, and containing a self-luminous mass 22, comprising a powder and an adhesive agent, such as thin 105 varnish, which latter serves to prevent escape of the powder from the tube before it is placed in the container 14. Inner receptacles of this nature can be made by filling a relatively long tube with the self-luminous 110

material and then breaking it into suitable lengths for use. The method of carrying out this operation is described and claimed in a copending application for patent.

5 Fig. 3 of my drawings also illustrates an alternative form of stopper for the outer container which may be used with any form of inner receptacle. This stopper is formed by injecting into the top of the container 14 10 a small quantity of water-glass, which, on hardening, forms a closure 15 of such a nature as to give it the appearance of forming a single homogeneous mass integral with the container 14 itself.

15 In Fig. 4 is shown still another form of interior receptacle. Here the self-luminous mass 10 is placed in a tube 23, sealed by fusion at one end only. The opposite end is closed, after filling, by inserting the end of a 20 glass rod coated with hot shellac or the like adhesive, and breaking off the inserted end to form a permanent stopper 24.

It is clear that various changes can be made in this device without departing from 25 the scope of my invention and I do not limit myself to the details herein shown and described.

What I claim is:—

1. A self-luminous device comprising an 30 outer translucent container, a hollow space in said container, a separate and individual container, luminous material in said second container, said second container being in said hollow space.

2. A self-luminous indicating device 35 adapted to be attached to a pull chain comprising a container having substantially thick translucent walls adapted to receive the actuating force of said chain, said container having a hollow space between said walls, a 40 translucent capsule containing a luminous material said capsule being contained in said hollow space and means near one end of said container for attaching the container to a pull chain.

45 3. A self-luminous indicating device comprising a translucent container, an elongated hollow space in said container, a narrow elongated capsule in said hollow space, a luminous material in said capsule, said capsule being sealed at both of its ends.

50 4. In a device of the class described, an outer transparent container having a groove near one end thereof, a thin metallic shell spun into said groove, and a wire loop having its ends inserted within said shell and bent outward against the same, said loop bearing against the outside and said ends against the inside of said shell so as to prevent rocking of the loop in any direction.

55 5. A self luminous attachment or pendant comprising an outer glass container, a self luminous element within the same, and a stopper of hardened water glass for said container.

60 In testimony whereof, I have affixed my signature to this specification.

REINER W. ERDLE.
